Primary Examiner — Elizabeth Albert(74) *Attorney, Agent, or Firm* — Daniel V. Thompson(57) **CLAIM**

The ornamental design for a side opening clipboard, as shown and described.

DESCRIPTION

FIG. 1 is a rear-facing perspective view of the side opening clipboard showing my new design;

FIG. 2 is a front-facing perspective view thereof;

FIG. 3 is a top plan view thereof;

FIG. 4 is a front side elevational view thereof;

FIG. 5 is a bottom plan view thereof;

FIG. 6 is a left-side elevational view thereof; and,

FIG. 7 is a right-side elevational view thereof.

The broken line showing of a clip is for the purpose of illustrating environmental structure and forms no part of the claimed design.
